TAPE CONTROLLING MEANS FOR NEWS
PROJECTING MACHINES

James W. Decker, New York, N. Y.

Application February 10, 1928, Serial No. 253,302

22 Claims. (Cl. 178—42)

This invention relates in general to news projecting machines and more especially to tape controlling mechanism which is effective gradually to start and stop the tape drawing device of a news projecting machine.

Among the objects of the present invention it is aimed to provide a tape controlling mechanism for a news projecting machine which will assist in absorbing the jumps or vibrations transmitted to the tape by the ticker and will in addition protect the tape against the jars that might be transmitted to the tape by the sudden starting or stopping of the tape drawing means. To this end, the present invention aims especially to provide a tape controlling device which embraces a jump absorbing device and tape drawing device cooperating with said jump absorbing device gradually to speed up from a dead stop when the ticker starts and gradually to slow down to a stop when the ticker comes to rest.

Specifically, the invention also aims to provide a resistance for controlling the speed of the driving means for the tape drawing device, which driving means operates with the jump absorbing device gradually to speed up the driving means from a dead stop when the ticker starts and gradually to slow down the driving means to a stop when the ticker comes to rest.

The invention still further contemplates the provision of an electric rheostat for controlling an electric motor constituting the driving means of a tape drawing device and a jump absorbing device cooperating with said rheostat to cause said electric motor gradually to speed up from a dead stop when the ticker starts and gradually to slow down to a stop when the ticker comes to rest.

These and other features, capabilities and advantages of the invention will appear from the subjoined detail description of specific embodiments thereof illustrated in the accompanying drawings in which

Figure 1 is a fragmental front elevation of one embodiment of the invention contemplating a friction resistance for controlling the driving means;

Fig. 2 is a fragmental end elevation partly in section of the embodiment illustrated in Fig. 1;

Fig. 3 is a section on the line 3—3 of Fig. 1;

Fig. 4 is a fragmental front elevation of another embodiment of the invention contemplating the use of a rheostat for an electric motor constituting the driving means in this embodiment;

Fig. 5 is a fragmental end elevation partly in

section of the embodiment illustrated in Fig. 4;

Fig. 6 is a front elevation of the motor and tape drawing device including a rewind for the embodiment illustrated in Fig. 4;

Fig. 7 is a plan of the mechanism illustrated in Fig. 6;

Fig. 8 is an enlarged fragmental plan showing the rheostat controlling lever and appurtenant parts of the embodiment illustrated in Fig. 4;

Fig. 9 is an enlarged fragmental end elevation of the mechanism illustrated in Fig. 8 and a diagrammatic view of the wiring for the rheostat and motor; and

Fig. 10 is a section on the line 10—10 of Fig. 8.

In the embodiment illustrated in Figs. 1, 2 and 3, there is shown a platform 1 on one side of which there is secured a frame 2 having a ticker 3, and on the other side a lamp housing 4 having an extension 5. The ticker, in the present instance, is equipped with a positive type wheel 6 for producing negative characters and is also provided with suitable feeding means not shown. The lamp housing 4 is provided with the usual lamp 7 for directing light rays to the lens 8, from which the light rays are projected onto the inclined mirror 9 formed at the bottom of the extension 5, from which the light rays are projected upwardly through the lens 10 at the light aperture at the upper end of the extension 5 and through the portion of the tape T passing across the light aperture.

The tape T, as shown in Fig. 1, passes from the ticker 3 under the roller 11 formed at the lower end of the arm 12 and then above the abutment 13 formed on the bracket 14 secured to the side of the extension 5. Above the abutment is formed a friction creating finger 15 for pressing the tape T against the abutment 13. From the finger 15, the tape passes across the light aperture to the positively driven roller 16 and then down either to a rewind roll or a suitable receptacle, not shown.

On the extension 5 is supported the bracket 17 having a housing 18 at its upper end for receiving the projecting lens, which receives the images of the tape projected by the light rays, and which projecting lens in turn projects the images to the mirror 19 formed in the frame 20 supported on suitable brackets such as the bracket 21, which is preferably secured to a wall 22 or the like. From the mirror 19 the images are projected onto the screen 23 in the housing 20.

The tape drawing roller 16 is connected to a suitable motor. In the present instance, there is illustrated a spring motor, the roller 16 being

fixed to the shaft 24 journaled in the bearing 25 extending from the bracket 26 which is preferably secured to the side of the extension 5. The shaft 24 is provided with a beveled gear 27 in mesh with the beveled gear 28 on the shaft 29, which has secured thereto a spur gear 30 in mesh with the pinion 31 mounted on the shaft 32, which has secured thereto a spur gear 33 in mesh with the idler 34 on the shaft 35.

The shaft 35 has a pinion 36 fixed thereon in mesh with the pinion 37 on the shaft 38, see Fig. 3, which shaft 38 has wound thereon the spring 39. The shaft 35 is provided with a suitable ratchet wheel 41 cooperating with the pawl 40 on the idler 34 so that the handle 42 on the shaft 35 may be actuated to wind up the spring 39 in the usual way.

The shaft 29 is also provided with the pinion 43 in mesh with the spur gear 44 on the shaft 45 provided with the broad flywheel 46. The flywheel 46 is adapted to cooperate with the brake shoe 47 secured to one end of the lever 48 fixed on the shaft 49, which is journaled in the upper end of the frame 26. The lever 48 passes through the slot 48a formed in the lower end of the arm 50 pivotally connected to the lever 51 pivotally connected to the bracket 17 at 52. The other end of the lever 51 is pivotally connected to the upper end of the arm 12. Whereby the lever 51 and arms 12 and 50 form a pivotally mounted device having one end engaging the tape adjacent the ticker and the other end operatively connected with the brake device including the brake shoe 47 and lever 48.

In the operation of this device, the printed face of the tape will face upward and be engaged by the roller 11, the roller 11 preferably engaging the tape between the two rows of printed matter on the same in the usual way. When the ticker stops, the spring motor will continue to operate to actuate the tape or drawing roller 16 against which the tape is impinged by the idler 53 secured at one end of the arm 54 pivotally connected to the frame 26. The tape drawing roller 16 will continue to cooperate with the idler 53 to draw the tape T until the loop or slack under the roller 11 has been dissipated or taken up, thereby raising the arm 12, in turn actuating the lever 51 to depress the arm 50 and thereby bringing the brake shoe 47 into engagement with the flywheel 46. As the pressure increases, due to the rise of the arm 12 and the depression of the brake shoe 47, the spring motor will gradually slow up and finally come to a dead stop.

Simultaneously, when the ticker again starts printing and feeding the tape, as the slack is formed under the roller 11 the arm 12 will gradually descend, thereby gradually releasing the brake shoe 47 from engagement with the flywheel 46, in turn gradually permitting the spring motor to pick up speed and increase the speed of the tape drawing roller 16.

In the embodiment illustrated in Figs. 4 to 10 inclusive, the controlling means for gradually slowing up the tape drawing means and gradually speeding up the tape drawing means, consists essentially in an electrical drive which will now be described.

In the embodiment shown, there is provided a frame having two platforms 55 and 56. On the platform 55 to one side thereof, there is mounted the bracket 57 for the ticker 58, which is provided with a negative type wheel 59 for forming positive type characters and suitable

feeding mechanism consisting of the rollers 60 and 61. To one side of the bracket 57 there is provided the lamp housing 62 having the extension 63. Between the ticker 58 and the extension 63 there is provided an angle plate 64 for causing the tape as it passes from the ticker to the projecting mechanism to bend at right angles so that its printed side will face downward when it passes through the projecting machine.

The lamp housing 62 in the present instance is provided with the usual lamp 64' for projecting light rays to the lens 65, from which the light rays are projected to the mirror 66 at the bottom of the extension 63, by means of which mirror 66 the light rays are projected upwardly through the light aperture formed at the upper end of the extension 63 to pass through the portion of the tape T crossing such light aperture, from which the light rays and resulting images are projected upwardly to the objective lens unit formed in the lens housing 67, by means of which objective lens unit the images are projected onto the mirror 68 formed in the frame 69 supported on the brackets, one of which, 70, is shown, which bracket 70 is preferably secured to a wall 71 or the like. Through the mirror 68 in the housing 69 the images are projected onto the screen 72.

The lens housing 67 is preferably secured at the upper end of the bracket 73 mounted on the extension 63.

The tape T after leaving the ticker 58 passes under the roller 74, from which the tape passes over the angle plate 64 and then over the finger 75 and past the light aperture 76, see Fig. 8. After passing the light aperture, the tape T will pass over the idler 77 and then pass down over the tape drawing roller 78, see Fig. 6, and preferably then pass to the rewind reel 79.

The tape drawing roller 78 is fixed on the shaft 80 journaled in the bearing 81 provided with a sheave 82, at one end, which sheave is connected to the sheave 83 by a belt 84. The sheave 83 is preferably mounted on a shaft 85 which has secured thereto a worm wheel 86 in mesh with the worm 87 on the shaft 88, which has fixed thereto a sheave 89 which is connected to the sheave 90 by the belt 91. The sheave 90 is fixed on the shaft 92 of the electric motor 93. The shaft 25 is also provided with a sheave 94 which is connected to the sheave 89 by the belt 96, preferably a yieldable spring belt. The sheave 95 is fixed on the shaft 97 which has mounted thereon the rewind reel 79.

On the bracket 98, preferably below the journal 81, there is pivotally mounted the bracket 99 having an idler 100 at its upper end. The bracket 99 has secured thereto an arm 101 provided with a weight 102 which is adjustably mounted on the arm 101 whereby the pressure to be exercised by the idler 100 on the tape T may be regulated, the idler 100 functioning to press the tape T into engagement with the tape drawing roller 78 so that the tape drawing roller 78 may effectively cause a drawing action to be exercised on the tape T.

The electric motor 93, as shown in Fig. 9, is preferably connected by the conductor 103 with the conductor 104 which is secured to the conductive arm portion 105 of the lever 106, the lever 106 having an insulated portion 107 for insulating the portion 105 from the remaining portion 108 of the lever 106, the roller 74 being pivotally mounted at the free end of the por-

tion 108 of the lever 106. The conductive portion 105 of the lever 106 is preferably provided with a brush 109 for successively cooperating with the contacts 110, 111, 112, 113 and 14.

The contact 110 is connected by the conductor 115 with the conductor 116, which conductor 116 is connected with the outlet plug 117, which in turn is connected by the conductor 118 with the motor 93. The conductor 116 is connected by the conductor 119 with one end of the resistance R. The other end of the resistance R is connected by the conductor 120 with the contact 113. The contact 112 is connected by the conductor 121 with the resistance R at the point 122 whereby the upper portion A of the resistance may be shunted out. The conductor 123 connects the contact 111 with the resistance R at the point 124 whereby the portions A and B of the resistance are shunted out. The contact 114 has no contact at all but constitutes a dummy forming the final location of the brush 109 where the current is cut off from the motor 93.

The brush 109, resistance R and connections, in the present instance, constitute a rheostat for gradually increasing the current fed to the motor and in turn gradually reducing the current fed to the motor. In other words, when the full loop or full slack is formed, as illustrated in Fig. 9, the roller 74 will be at its lowest position and the brush 109 will engage the contact 110, which contact by means of the conductor 115 will permit the full current to pass to the motor 93 without going through any part of the resistance R.

When the ticker stops and the tape drawing roller 78 continues to operate, it will take up the slack, causing the roller 74 to rise and therewith causing the brush 109 to descend into engagement with the contact 111, when by means of the conductor 123, the current will be retarded through the portion C of the resistance R and thus slow down the speed of the motor 93 in turn to decrease the speed of the tape drawing roller 78. In turn, as the slack is taken up, the brush 109 will next engage the contact 112, when by means of the conductor 121 the current will be caused to pass through the portions B and C of the resistance R and thus further retarded, further to slow down the motor 93 and therewith the tape drawing roller 78. As the brush 109 continues down to engage the contact 113, it will cause the current to pass through the entire length of the resistance R before passing to the motor 93 and thus still further slow down the motor 93 and the tape drawing roller 78, and when the brush 109 still further descends into engagement with the element 114 it will shut off the current to the motor 93 to cause the same to come to rest.

In turn, when the ticker starts to operate and the slack begins to form, the roller 74 will first descend sufficiently to permit the brush 109 to engage the contact 113 and as the slack continues the brush 109 will gradually rise to engage successively the contacts 112, 111 and 110 to increase the speed of the motor 93. The roller 74 may be caused to descend with the slack in the tape T by any suitable means; in the present instance, the arm 108 being provided with the extension 125 and weight 126, the weight 126 being adjustably mounted on the extension 125 to regulate the pressure to be exercised by the roller 74 on the tape T.

It is obvious that various changes and modifications may be made to the details of construction without departing from the general spirit

of the invention as set forth in the appended claims.

I claim:

1. In a stock quotation projection machine having a ticker for intermittently discharging tape, the combination with a tape support having a light aperture, a tape drawing device for smoothly drawing the tape as it is discharged across said support, driving means for said tape drawing device, speed changing means supplemental to the inertia effect of the driving means, comprising a variable speed regulator and cooperating with the inertia effect of the driving means for gradually bringing said driving means to a stop when the discharge of the tape ceases and for gradually causing said driving means to pick up speed when the discharge of the tape again starts.
2. In a stock quotation projection machine having a ticker for intermittently discharging tape, the combination with a tape support having a light aperture, of a tape drawing device for smoothly drawing the tape as it is discharged across said support, driving means for said drawing device, a slack sensing device cooperating with the tape in advance of said support, a speed changing device for said tape drawing device comprising a variable speed regulator to advance the tape at the rate at which it is being discharged, and means operatively connecting said slack sensing device with said speed changing device whereby said speed changing device will be effective gradually to slow up the operation of said tape drawing device as the tape ceases to discharge and will cause said tape drawing device gradually to pick up speed when the discharge of tape again starts.
3. In a stock quotation projecting machine having a ticker for intermittently discharging a tape, and a projection mechanism having a support provided with a light aperture, the combination including a tape drawing device for drawing the tape as it is discharged from said support, a speed controlling device to correspond to the rate at which it is ejected from the ticker for controlling the speed of said tape drawing device and a finger adapted to engage the tape in advance of said support and operatively connected to said speed controlling device, said finger being responsive to the tension in the tape to actuate said speed controlling device in turn to control the speed of the tape drawing device.
4. In a stock quotation projecting machine having a ticker for intermittently discharging a tape and a projection mechanism having a support provided with a light aperture, the combination with a tape drawing device adapted to feed a tape across said support as the tape is discharged, a variable speed controlling device for controlling the speed of said tape drawing device to correspond to the rate at which it is ejected from the ticker, a pivotally mounted lever, and a finger on one end of said lever adapted to engage the tape in advance of said support and responsive to the tension in said tape, the other end of said lever being operatively connected to said speed controlling device to control the speed of the tape drawing device.
5. In a stock quotation projecting machine having a ticker for intermittently discharging a tape and a projecting mechanism having a support provided with a light aperture, the combination with a tape drawing device for drawing the tape across said support as it is discharged, an electric motor operatively connected to said

tape drawing device, a rheostat for controlling the speed of said electric motor, a pivotally mounted lever, a finger on one end of said lever adapted to engage the tape and responsive to the tension of the tape, a brush operatively connected to the other end of said lever, and a plurality of contacts associated with said rheostat and adapted to cooperate with said brush to vary the resistance connected to said motor thereby to control the speed of said motor and in turn the speed of said tape drawing device.

6. In a stock quotation projecting machine having a ticker for intermittently discharging a tape and a projecting mechanism having a support provided with a light aperture, the combination including a tape drawing device for drawing the tape across said support as it is discharged, an electric motor operatively connected to drive the tape drawing device, a pivotally mounted lever, a finger on one end of said lever adapted to engage said tape and responsive to the tension in said tape, and a rheostat operatively connecting the other end of said lever with said motor whereby the movement of said lever due to the tension in the tape will in turn operate the rheostat to control the speed of said motor and thereby the speed of said tape drawing device.

7. In a stock quotation projecting machine having a ticker for intermittently discharging a tape and a projecting mechanism having a support provided with a light aperture, the combination including a tape drawing device for drawing the tape across said support as it is discharged, and an electric motor operatively connected to drive said tape drawing device, a pivotally mounted lever, a finger on one end of said lever adapted to engage the tape, and responsive to the tension in the tape, and a rheostat operatively connecting the other end of said lever with said motor whereby the movement of said lever due to the tension in the tape will in turn operate the rheostat to control the speed of said motor and thereby the speed of said tape drawing device, said finger engaging the tape in advance of the projecting mechanism.

8. In a stock quotation projecting machine having a ticker for intermittently discharging a tape and a projecting mechanism, the combination with a tape support having a light aperture, a tape drawing roller for drawing the tape through the projecting mechanism as it is being discharged, a re-wind reel for winding by the tape as it leaves the support, an electric motor operatively connected to said tape drawing roller and re-wind reel, said tape drawing roller cooperating with said ticker to draw the tape across said support and feeding it to said re-wind reel, a variable speed controlling device for controlling the speed of said motor to correspond to the rate at which it is ejected from the ticker, and a loop forming device for forming a loop in the tape in advance of said projecting mechanism and responsive to the tension in the tape, said loop forming device being operatively connected to said speed controlling device to actuate the same and thus control the speed of said motor.

9. The combination with a device for printing characters on a tape, of means operating substantially at constant speed for moving said tape through a projection field, and means for substantially changing the operative speed of said means in accordance with the rate at which the tape is ejected from said device.

10. In combination, a source of tape, a tape support, a tape puller, means for operating said tape puller at one speed when a predetermined amount of tape forms between the source and support, and means for operating said tape puller at an appreciably lower speed when the tape between the source and support decreases to a predetermined amount, means to arrest the movement of the tape when the tape between the source and support decreases to a still smaller amount and means for maintaining said tape at rest until an appreciable amount thereof corresponding to a plurality of characters again accumulates between the source and support.

11. In a device of the character described, the combination with a projection means toward which a character-bearing tape is movable after ejection from a recording means under the control of the feed mechanism thereof, an electrical take-up motor operating independently of said feed mechanism for moving said tape past the projection axis of said projecting means, variable resistance in circuit with said motor, supporting means for said tape in its path of travel from said recording means to said projection axis positioned to provide a gap between said recording means and said projection axis for a loop of said tape, and control means actuated by said loop for varying said resistance to vary the speed of said motor proportional with the feed speed of the tape whereby the speed of tape movement past said projection axis is decreased while increasing the duration of the periods during which tape is moved past said axis, said control means comprising a switch contact member having an actuating member connected thereto for moving said contact member in either of opposite directions to change the speed of said motor.

12. In a projection system, the combination with a projection field toward which a character-bearing tape is fed from a tape roll by the feed mechanism of a printing device at varying rates of speed, of a motor operative independently of said feed mechanism for pulling said tape through said projection field, tape-controlled means for starting and stopping said motor, and means operating in accordance with the rate at which tape is fed from said printing device for operating said motor at a speed proportional to the rate of tape feed, said last named means comprising a switch contact member having an actuating member connected thereto for moving said contact member in either of opposite directions to change the speed of said motor.

13. In a projection system, the combination with a projection field toward which a character-bearing tape is fed from a tape roll by the feed mechanism of a printing device at varying rates of speed, of a motor operative independently of said feed mechanism for pulling said tape through said projection field, tape-controlled means for starting and stopping said motor, and tape-controlled means operating in accordance with the rate at which tape is fed from said printing device for operating said motor at a speed proportional to the rate of tape feed, said last named means comprising a switch contact member having an actuating member connected thereto for moving said contact member in either of opposite directions to change the speed of said motor.

14. In a projection system, the combination with a projection field toward which a character-bearing tape is fed from a tape roll by the feed mechanism of a printing device at varying rates

of speed, of a motor operating independently of said feed mechanism for pulling said tape through said projection field, and means operative after said motor has been brought to normal speed for varying the speed thereof, said means serving to vary the speed of said motor without discontinuing the operation thereof, said means comprising a switch contact member having an actuating member connected thereto for moving said contact member in either of opposite directions to change the speed of said motor.

15. In a projection system, the combination with a projection field toward which a character-bearing tape is fed from a tape roll by the feed mechanism of a printing device at varying rates of speed, of a motor operating independently of said feed mechanism for pulling said tape through said projection field, and means for starting and progressively increasing the speed of said motor to bring it to normal speed, said means being thereafter operative to vary the speed of said motor without discontinuing the operation thereof, said means comprising a switch contact member having an actuating member connected thereto for moving said contact member in either of opposite directions to change the speed of said motor.

16. In a stock quotation projection machine having a ticker for intermittently discharging tape, the combination with a support, of a tape drawing device for drawing the tape across said support as it is discharged, driving means for actuating said drawing device, a control including a brake drum operatively associated with said driving means, a friction brake device positioned to be pressed into stopping engagement with said drum, and a pivotally mounted device having one end engaging the tape between said ticker and said support and the other end operatively connected with said brake device, said pivotally mounted device being rocked in response to deflections in the tape in turn to actuate said brake device into or out of controlling engagement with said drum.

17. In a stock quotation projection machine having a ticker for intermittently discharging tape, the combination with a support, of a tape pulling sheave for drawing the tape across said support as it is discharged, a brake drum operatively associated with said tape pulling sheave, a friction brake device, and a pivotally mounted device having one end engaging the tape between said ticker and said support and the other end operatively connected to said brake device in position to cooperate with said brake drum, said piv-

otally mounted device being rocked in response to deflections in the tape in turn to actuate said brake device into or out of controlling engagement with said drum in turn to control said tape pulling sheave.

18. In combination a source of printed tape, a support across which said tape is adapted to pass, means at the forward end of said support for holding said tape in frictional contact with the support, tape pulling means at the opposite side of the support, a brake associated with the pulling means and means controlled by tension of the tape between the tape source and the pulling means for applying said brake to arrest the movement of the tape across the support.

19. In combination a source of printed tape, a support across which said tape is adapted to pass, means at the forward end of said support for holding said tape in frictional contact with the support, tape pulling means at the opposite side of the support, a brake associated with the pulling means, a pivoted roller about which the tape is passed and means controlled by pivotal movement of said roller, caused by slack take-up of said tape for actuating said brake to arrest the movement of the tape across the support.

20. In combination a source of printed tape, a support across which said tape is adapted to pass, means at the forward end of said support for holding said tape in frictional contact with the support, a pair of opposed rollers at the opposite side of the support between which said tape passes, a friction brake associated with one of said rollers and means actuated by the tape for applying said brake to arrest the movement of said roller whereby to stop the movement of the tape across the support.

21. In combination a support, a source of tape disposed at one side of said support, a pair of opposed rollers disposed at the opposite side of the support between which said tape passes, a friction brake associated with one of said rollers and means actuated by the tape for applying said brake to arrest the movement of said roller, whereby to stop the movement of the tape across the support.

22. In combination a support, a source of tape disposed at one side of said support, a pair of opposed rollers disposed at the opposite side of the support between which said tape passes and means controlled by slack take-up of the tape for applying a gradual braking action to one of said rollers whereby to arrest the movement of the tape across the support.

JAMES W. DECKER.
